UNITED STATES PATENT OFFICE

162,262

RIBBON DISPLAY STAND

Harry Veeder, New York, N. Y.

Application September 19, 1950, Serial No. 12,261

Term of patent 7 years

(Cl. D80—9)

To all whom it may concern:

Be it known that I, Harry Veeder, a citizen of the United States of America, residing in New York city, county of New York and State of New York, have invented a new, original, and ornamental Design for a Ribbon Display Stand, of which the following is a specification, reference being had to the accompanying drawing, forming part thereof, wherein,

The characteristic features of my design reside in the portions shown in full lines in the drawing.

I claim:

The ornamental design for a ribbon display stand, substantially as shown and described.

HARRY VEEDER.
